United States Patent Office.

ALFRED BLISS, OF NEW YORK, N. Y.

Letters Patent No. 84,406, dated November 24, 1868.

IMPROVEMENT IN LAMP-BURNERS.

The Schedule referred to in these Letters Patent and making part of the same.

To all whom it may concern:

Be it known that I, ALFRED BLISS, of the State, county, and city of New York, have invented certain new and useful Improvements in Burners for Kerosene and other analogous Lamps; and I hereby declare that the following is a full, clear, and exact description thereof, reference being had to the drawing, which accompanies and forms a part of this specification.

Of this drawing—

Figure 1 is a central vertical section of a burner and chimney containing my improvements;

Figure 2 is an elevation of the same burner without the chimney; and

Figure 3 is a top view of the burner, showing the ring or bead, which will be hereinafter described.

In the drawing—

A represents the body of a kerosene or other analogous burner, which may be constructed in the usual manner, and may be provided with the wick-tube, cone, air-passages, and other appliances customary in such burners.

B B are the springs or guides which hold the chimney.

I am well aware that springs of many various forms have long been used in kerosene-burners for securing the chimney, but in all the instances of them with which I am acquainted, the operative portion of the spring or springs has been near to or above the top of the body of the burner, and the lower edge of the chimney has also usually been required to be secured by some part of the burner-body, and has not been held by the springs. Such springs answer sufficiently well for some purposes, but they differ essentially from my improved combination, and are incapable of effecting the results which I obtain.

By inspection of the drawing, it will be perceived that my springs or guides, instead of originating or commencing, so to speak, at a point below the top of the body of the burner, and extending up to or above such top, commence at the top thereof, and extend nearly or quite to the lower part of the burner-body, and, instead of having their operative portions at their upper ends, have them at their lower ends, thus completely reversing the arrangement and mode of operation of the springs heretofore used in burners.

By means of this method of construction, I am enabled to carry out the first and second portions of my invention, inasmuch as the springs or guides which I employ, when used in connection with a suitable chimney, one convenient form of which is represented in the drawing, not only perform the office of securing the chimney in proper position as firmly as any springs heretofore used in burners can do, but, also, by reason of the fact that the lower edge of the chimney is carried and firmly held by the lower ends of the springs or guides, as seen in the drawing, without requiring to be supported by any part of the burner-body, enable the lower portion of the chimney to extend, as represented in the drawing, below, more or less, as may be preferred, of the air-passages of the burner, and, thereby, to mate

rially aid in protecting the flame from being injuriously affected by currents of air. At the same time there is a free and ample supply of air afforded to all parts of the burner, as may be clearly seen in the drawing, and, consequently, the burner and oil are kept cool; and, as by my mode of construction the lower end of the chimney is not at any time closed up by any part of the burner, but remains constantly exposed directly to the air which circulates freely around it, its base is always preserved in a very much cooler condition than in any other lamp of this class heretofore known.

This portion of my invention also, as will be seen in the drawing, enables me to employ a much shorter wick-tube, and, consequently, to place the cone or deflector much lower than has heretofore been practicable in lamps of this variety, and as this result brings the top of the wick very near to the contents of the oil-reservoir, I am able to fully draw out all the oil therein, and burn it advantageously, without producing any inconvenient incrustation of the wick.

The ring or bead above referred to constitutes the third portion of my invention, and is shown in the drawing at c. When constructed as I prefer, it is formed upon and makes a part of the lower edge or flange of the cone or deflector of the burner, and its office is to present a surface attached to or connected with the cone, and projecting sufficiently from the main body of the cone to enable some portion of a properly-formed chimney to come in contact with it when the chimney is in its proper position, and thereby hold the cone securely down to its place.

This result is accomplished in the form of my invention, which is illustrated in the drawing, by making the chimney with what I term an "inset" or inwardly-extending surface or projection, as seen at d, adapted to touch and rest upon the ring or bead c, when the chimney is in its proper position for use, so that the chimney will hold it firmly down.

But, although this is the mode which I prefer of carrying out this part of my invention, any other equivalent mode may be substituted, if desired; and any suitable form of chimney may be used in place of that shown in the drawing.

If desired, also, the ring or bead may extend around only a portion of the circumference of the flange of the cone, or may be formed only at intervals around such circumference.

Having thus described my invention,

What I claim as new, and desire to secure by Letters Patent, is—

The combination, with the burner of a kerosene or other lamp, of a removable cone or deflector, so constructed, that when the chimney and cone or deflector are in position for use, the chimney will rest upon the bead or ring and retain the cone in place, substantially as described.

ALFRED BLISS.
